UNITED STATES PATENT OFFICE.

FRANCOIS RENÉ MARCEL, OF BROOKLYN, NEW YORK.

APPARATUS FOR WAVING HAIR.

Application filed September 18, 1923, Serial No. 663,413. Renewed September 21, 1926.

My present invention relates to hair waving devices and while it is adapted for use generally in waving hair, its greatest usefulness is in producing what is known as a permanent wave in the human hair. Heretofore it has been common practice in producing the permanent wave to twist a lock of hair around a rod or curler, to then either directly apply a chemical to the hair or else 5 wrap a cloth or paper covering on the hair which covering contained a chemical, and to wet the same, enclose these in a paper container and then apply over the whole an electric heater. When the current was passed 10 through the electric heater, the heat generated vaporized the chemical and the water and this, together with the heat, set or made permanent the wave in the hair. In this process, it was necessary, in order to make 15 the wave permanent, to carry the heating operation to a point where all of the liquid in or around the hair was completely vaporized and driven off so that the hair at the end of the operation was dry. On the other 20 hand, if the heat were applied beyond the point where the hair was fully dried it often resulted in burning or scorching the hair and sometimes the whole lock of hair was burned completely off the head. If the 25 degree of heat were lowered to a point where the hair could not be burned after it became fully dried, then the operation was too prolonged and the wave would be less permanent. In the operation of such heaters it 30 was difficult to carefully watch each lock of hair during the baking operation, not only because of the number of such heaters in operation at one time, but also because it was necessary to remove the heater, thus losing 35 some of the heat, but even when the heater was removed it was not always possible to determine the dryness of the hair, especially where it was enclosed in a paper tube. The object of my present invention, 40 among other things, is to provide a heater for permanent waving which will be automatic in its operation. By this, I mean that the electric current when once turned on will 45 generate heat sufficient to vaporize all of the moisture in or around the hair and 50 which will carry this heating operation on in the most efficient manner and when the moisture has been entirely vaporized and driven off the electric current will cease to 55 flow through the heater so that the heating process is automatically arrested when the hair has been fully baked. The present device is not only adapted for use by professional hair dressers but it is also adapted 60 for use by the public generally. In using the present device a woman may twist a lock of hair around the curler and supply the necessary chemical and moisture and 65 enclose the whole in a tube if desired, place the heater over the lock of hair and curler, 70 turn on the current, and await the completion of the operation without fear of burning the hair. When all of the moisture has been vaporized and driven off, the electric 75 current is automatically shut off because the circuit during the process is maintained through the moisture as a part of the conductor between the electrodes. The broad 80 feature of my invention, therefore, resides in using the moisture for completing the circuit between the electrodes so that when the moisture has been eliminated no current can flow and therefore the baking process 85 can not be carried to a point where it can injure the hair. In the preferred form of my invention no resistance wire is needed within the heater which is applied to the hair, as a tube of asbestos may be used for an electrode. This will hold sufficient moisture for the waving operation and when the 90 moisture has been driven off the asbestos, being an insulating material, will not conduct the current between the two electrodes. The liquid itself will have sufficient resistance to the flow of the electric current to 95 cause the heat required for vaporizing the liquid.

In the drawings forming part of this application, Figure 1 is an elevation of my improved heater in the preferred form,

Figure 2 is a longitudinal sectional view thereof, showing the same in actual operation,

Figure 3 is an enlarged sectional view taken on the line 3—3 of Figure 2,

Figure 4 is a sectional view taken on the line 4—4 of Figure 2,

Figure 5 is a diagrammatic view of the electric circuit,

10 Figure 6 is an elevation, partly in section, of a modified form of the invention,

Figure 7 is a similar view of the curler used in this form,

15 Figure 8 is an enlarged sectional view taken on the line 8—8 of Figure 7, and

Figure 9 is an enlarged sectional view taken on the line 9—9 of Figure 7.

I will first describe the form of my invention shown in Figures 1 to 5. In this

20 form I have shown a lock of hair 1 wound around the curling rod 2 and around the lock of hair, close to the head, there is tied a short tube 3. The heater consists in part

25 of a cylindrical shell 4 which is open at one end to permit it to be placed over the hair and curler and the other end is closed by the screw cap 5 which is provided with apertures 6 to allow the vapor formed within the heater to pass out. Within the cyl-

30 inder 4 there is wound or coiled a sheet of absorbent material 7 and for this purpose I prefer to use asbestos because it will not only hold the liquid but it is porous and non-

35 inflammable. It will be understood, how- ever, that I am not limited to the use of this particular material nor to the form in which it is used. This roll or coil of asbestos fits closely inside the cylinder 4 and I have

40 shown it extending from the open end 8 of the cylinder to the point 9 which is suffi- ciently long to inclose the curler and a lock of hair of any length. I have arranged

45 within this roll or coil of asbestos a tube or cylinder 10 which fits closely against the roll of asbestos and it is provided with a number

50 of apertures 11 throughout its surface which will permit vapors to pass through. This tube forms one of the electrodes of the

55 heater and electrical connection is made therewith in the following manner. The cap 5 which closes one end of the cylinder 4 is provided with a plug 12 and through

55 a bushing extend sleeves 13 of insulating material and within the latter there is held

60 a rod 14 to which is bolted by the bolt 15 a double arm contact spring. One arm 16 of this contact spring projects into the tube 10 and presses against its inner surface to make

65 electrical contact therewith. The other arm 17 of this spring projects between two of the layers of the asbestos coil 7 and is there- fore in electrical contact with portions of the coil in addition to the contact made through the arm 16. From this it will be apparent

65 that one terminal of the electrical circuit is

connected with the inner tube 10 and to the coil of asbestos. There is a metal sleeve 18 surrounding the rod 14, and this projects into the insulated handle 19 and it is pro- 70 vided with a cap 20 from which latter projects a wire terminal 21 the latter extending into the perforated screw cap 20 arranged on the outer end of the handle. There is another terminal wire 22, extending into the cap 20 and this is attached to the sleeve 23 which is in electrical connection through the plug 12 and the cap 5 with the cylinder 4. The cable 24 running from a suitable socket 75 in some part of an electrical circuit or source of supply, is provided with small tubes 25 80 each connected with one of the wires in the cable. These small tubes slide over the terminal wires 21, 22 to connect the electrodes of the device into the electric circuit. From the above it will be apparent that one side 85 of the circuit is connected with the inner tube 10 and therefore with the asbestos coil 7 and the other side of the circuit is connected with the cylinder 4 which forms another electrode. 90

I provide means for controlling the current which is permitted to flow through the heater and means for regulating the current and I have also provided a lamp which will indicate the condition existing at all times 95 in the heater. In Figure 5 I have shown a resistance 26 connected in series between the wires 27, 28, which connect with one of the tubes 25 and this resistance may consist of a coil of resistance wire and a block of insulat- 100 ing material or it may consist of an open air-cooled coil of resistance wire, the particular form of resistance being immaterial to the operation of the device. In addition to the fixed resistance, I have shown an ad- 105 justable resistance 29 connected between the two wires 27, 28 and this is to regulate the amount of current flowing through the cir- 110 cuit over and above the current which is passed by the resistance 26. In addition to 110 these resistances, I have shown a third re- sistance in the form of a lamp 30 in series between the wires 27, 28.

Operation.

115 The lock of hair is wound upon the curler and if desired the chemical for making the wave permanent may be directly applied to the hair or a wrapping of cloth or paper saturated with the chemical may be wound around the hair both of these methods being 120 in general use. The heater is dipped into water or other liquid so that some of it is absorbed by the coil of asbestos 7; the heater is withdrawn from the liquid after some of 125 it has been absorbed by the asbestos and the heater is then placed over the curler and hair so that the open end of the heater projects into the open end of the paper tube 3. The current is then turned on in the electric 130

circuit and it flows through the wires 27, 28, and 31 and through the small tubes 25 to the wire terminals 21, 22. One side of the circuit is connected through the spring 5 arms 16, 17 to the inner electrode 10 and the other side of the circuit is connected to the cylinder 4, which forms the other electrode in the circuit. The water or other liquid held in the asbestos 7 is a partial conductor 10 of electricity and therefore the circuit between the electrodes is completed through this liquid and the current is allowed to flow through the entire circuit. However, the liquid in the asbestos pad is of high resistance 15 and this causes heat to be generated in the heater, which vaporizes the liquid in the asbestos coil and any liquid in the chemical applied to the hair. The vapors from the asbestos coil pass through the apertures 11 20 in the tube 10 and pass around and through the hair so that the latter is subjected to the action of the heat and the chemicals which are to fix the wave. Some of the vapors may pass out of the open end of the 25 heater and these are deflected away from the head by the tube 3. Some of the vapors may pass out through the openings 6 in the cap 5. When the operation first starts, the lamp 30 will burn more brightly because the asbestos coil 7 will at that time have the maximum amount of liquid in it and therefore it will permit the passage of a greater amount of electricity between the electrodes. 30 As the liquid in the asbestos coil is gradually vaporized and the vapors are driven off, the lamp gradually decreases in brilliancy, due to the decrease in the flow of electricity between the electrodes, so that the lamp, by 35 its decrease in brilliancy, indicates the extent of moisture within the heater and therefore the progress of the operation. When most of the liquid has been vaporized and driven off from the asbestos coil the lamp will finally show no light whatever and the 40 current should remain turned on for several minutes after the lamp ceases to show red in the filament. However, the time at which the current may be turned off after this point has been reached is in no sense 45 critical for the following reason:—As the liquid is vaporized and driven off, the point is finally reached where the asbestos coil 7 becomes dry and all of the vapors from the liquid and the chemicals have been driven off and then there will be no conducting 50 medium through which current can pass between the two electrodes; and when this condition is reached the current automatically stops flowing through the circuit regardless 55 of whether the current is turned off at the socket on the main wires or not. Therefore it is only necessary for the operator to turn on the current at the beginning of the operation, regulate the current to suit conditions, 60 and leave the current turned on any length 65 of time after the filament of the lamp ceases to show red; and the current is automatically cut off when the vapors have been entirely driven off, so that once the hair is dried, no heat is further generated in the device and 70 no current flows through the circuit. It will be apparent, also, that no resistance wire need be used in the heater and all danger of burning or scorching the hair or the head is entirely eliminated. The switch 33 may be 75 adjusted on the resistance 29 to regulate the flow of current so that the speed of operation of the device may be regulated to suit conditions. This simply regulates the flow 80 of current over and above that which flows through the fixed resistance 26 and the lamp 30. It will be apparent from the above description that where the present device is used in numbers at one time upon the same head, that the operator need give no attention while the several heaters are operating, to the question of whether a particular heater has completed the baking operation, because when the operation of any particular heater has once been completed, no current 85 can afterwards flow through the circuit of that heater and therefore the operation is automatically terminated on each heater. This automatic action makes the present device adapted for use by the public generally 90 at home whereas in all former devices for permanent waving there has been considerable danger to the operator and danger of burning the hair where the operator was not especially skilled in the work. With the 95 present device no skill is required in determining when the baking operation has been carried to the proper point.

In the form of my invention shown in 100 Figures 6 to 9 inclusive, I have used the 105 curler as one of the electrodes. In this form, the curler 35 consists of a metal tube having a number of perforations 36, and this is the member on which the lock of hair is wound and it corresponds in function with the member 2 in the first form of the invention. The 110 body of asbestos 37 is inserted in this curler and one of the contact members 38 projects into this coil and makes contact therewith. The other end of this strip 38 projects beyond the curler. Another contact member 39 rests against the inner surface of the curler 35 and it has an end projecting beyond the same. Exterior of the curler the 115 ends of the members 38, 39 are properly spaced by insulating material 40. The handle 41 in this instance is connected with the cable wires 42, 43 the latter being connected with the small tubular connecting members 120 44, 45 which are embedded in the insulating material 46 within the handle member. The handle member is moved toward the curler and the curler and the terminals 38, 39 slide into the members 44, 45 and this connects the 125 former in the electric circuit. It will be 130

understood that the same resistance members and lamp may be used in connection with this form of my invention as shown in relation to the first form. In using this form 5 of the invention the curler is dipped into water or other fluid to moisten the coil 37 and then the lock of hair is wound around the curler and if desired a plain tube 46 may be placed over the lock of hair to confine the 10 heat. It will be understood that the waving chemical is applied to the hair in any of the customary ways and when the handle member 41 is slipped over the terminals 38, 39 and the current is turned on the circuit will 15 be completed through the liquid in the asbestos coil 37. The operation will therefore be the same as in the first form of the invention with the exception that the vapors will be thrown off from within the coil of hair 20 instead of being generated around the coil of hair. In other respects the device will operate automatically the same as the first form.

The method herein described in connection 25 with the apparatus consists broadly of waving hair by means of an electrical heating unit in which a liquid or moisture of sufficiently high resistance to cause vaporization completes the circuit between electrodes 30 so that the current is automatically shut off when the liquid has been driven off.

Having described my invention, what I claim is:

1. A device for treating hair comprising 35 an electric heater adapted to be applied to the hair to heat it and including electrodes between which the circuit is adapted to be completed by moisture of high resistance, whereby when said moisture has been driven off the circuit will be automatically broken.

2. A device for treating hair comprising 45 an electric heater adapted to be applied to the hair to heat it and including electrodes and means for holding moisture between said electrodes, the electric circuit between said electrodes being completed by moisture held by said means, whereby when said moisture has been vaporized and driven off the circuit between said electrodes will be automatically 50 broken.

3. A device for treating hair comprising 55 an electric heater adapted to be applied to the hair to heat it and including electrodes and a body of asbestos for holding moisture and arranged between said electrodes, the electric circuit between said electrodes being completed by moisture held in said body of asbestos, whereby when said moisture has been vaporized and driven off the circuit 60 between said electrodes will be automatically broken.

4. A device for treating the hair comprising 65 an electric heater adapted to be applied to the hair to heat it and including electrodes, and a body of absorbent material for

holding moisture and arranged between said electrodes, the electric circuit between said electrodes being completed by moisture held in said absorbent material whereby when said moisture has been vaporized and driven off, the circuit between said electrodes will be automatically broken, said absorbent material being arranged whereby the vapors from the moisture therein will be applied to the hair.

5. A device for treating hair comprising an electric heater including a tubular body adapted to be placed over a lock of hair, said body including electrodes and a body of moisture holding material between said electrodes.

6. A device for treating hair comprising an electric heater including a tubular body adapted to be placed over a lock of hair, said body comprising an outer, cylindrical shell 85 and an inner cylindrical member forming electrodes, and a body of moisture holding material between said shell and said inner cylindrical member, the circuit between said electrodes being completed between said electrodes by the moisture in said body of moisture holding material.

7. A device for treating hair comprising an electric heater including a tubular body adapted to be placed over a lock of hair, said body comprising an outer cylindrical shell and an inner, perforated cylindrical member, forming electrodes, and a body of moisture holding material between said electrodes, the circuit between said electrodes being completed by the moisture in said body of moisture holding material.

8. A device for treating hair comprising an electric heater including outer and inner tubular members, a body of asbestos between 105 said tubular members for holding moisture, the electric circuit in said heater being completed through the moisture in said body of asbestos, whereby the electric circuit will be broken when said moisture has been driven off.

9. A device for treating hair comprising an electric heater adapted to be applied to the hair to heat it, including electrodes, means interposed between said electrodes for holding moisture whereby the electric circuit between said electrodes will be completed through the moisture, and means associated with the circuit for indicating whether current is flowing in the circuit.

10. A device for treating hair comprising an electric heater adapted to be applied to the hair to heat it, including electrodes, means interposed between said electrodes for holding moisture whereby the electric circuit between said electrodes will be completed through the moisture, an electric circuit in which said electrodes are included, and a lamp in said circuit for indicating when current is flowing therein, whereby it 130

may be determined from the exterior of said heater when the moisture has been driven off.

11. A device for treating hair comprising an electric heater adapted to be applied to the hair to heat it and including electrodes and a body of absorbent material arranged between said electrodes, the electric circuit between said electrodes being completed by

moisture held in said body of absorbent material, whereby when said moisture has been 10 driven off the circuit between said electrodes will be automatically broken.

Signed at the city, county and State of New York, this 27th day of August, 1923.

FRANÇOIS RENÉ MARCEL.
